UNITED STATES PATENT OFFICE.

JOSEPHINE M. ST. CLAIRE, OF CEDAR RAPIDS, IOWA.

CORSET.

SPECIFICATION forming part of Letters Patent No. 322,497, dated July 21, 1885.

Application filed April 14, 1885. (No model.)

To all whom it may concern:

Be it known that I, JOSEPHINE M. ST. CLAIRE, a citizen of the United States, residing at Cedar Rapids, in the county of Linn and State of Iowa, have invented certain new and useful Improvements in Corsets, of which the following is a specification.

The object of my invention is to produce a corset which shall be more durable, comfortable, and perfectly conformable to the figure than those in general use.

The invention consists in the peculiar construction and arrangement of the several parts to this end, as will be hereinafter more fully set forth.

In the accompanying drawings, Figure 1 represents a front view of a corset embodying my invention; Fig. 2, a back view of the same; Figs. 3, 4, and 5, sectional views of the front, showing the manner of attaching the busks to the corset; and Fig. 6 a cross-section of a corded portion of the corset and a "bone" or steel attached thereunder.

Similar letters of reference indicate corresponding parts.

The corset consists, essentially, of seven sections on each side, or a two-part corset composed of fourteen principal parts, A B C D G H I, respectively. These are cut in forms that need not now be particularly described. Their general shape will be seen in Figs. 1 and 2, where the seams are indicated by dotted lines.

The chief objects to be attained are simplicity, durability, comfort, neatness, and a good fit. To secure these ends I have introduced the following improvements.

It will be noticed that the corset is cut high at the front and back. In the ordinary corset the top in front extends to about midway of the breast, and is practically straight across. The result of this is that with a person very fully developed there is a protrusion of the bust above this line, and in the case of a spare person a sudden and unsightly falling away, noticeable notwithstanding the most careful arrangement of the outer garments. So, also, at the back, the top of the corset, which usually reaches slightly above the bottom of the shoulder-blades, is all too plainly indicated. To avoid this unpleasant advertisement of the corset, and secure a more perfect fit in the ar-

ticle itself, as well as the outer garments, the front is extended to the upper part of the bust, the section A being continued up to the shoulder, forming a yoke, as shown. The busks are preferably made to terminate at a point near the middle of the bust, above which the corset is only stiffened by cording. This admits of the corset conforming to the body of the wearer, and, to a reasonable extent, of such an artificial conformation as vanity or necessity may suggest, without a too obvious disclosure of the means employed.

In practice I cut the corset to order, insuring a perfect fit; but made from a model for custom-trade, the corset will be found to satisfy all the requirements in this respect. At the back the sections B B, forming the main portions, are extended nearly or quite to the top of the shoulder-blades, the bones terminating a short distance below that point, and upon the shoulder as in front. Thus no unsightly ridge is left exposed at the most prominent point of these shoulder-blades, as is the case with many corsets. The shoulder-pieces are united by elastic straps *a a*, which, being at the top of the shoulder, admit of the arm being raised or moved otherwise without disturbing the position of the corset elsewhere, and especially without drawing and tearing it under the arm, as in the case of many corsets provided with a shoulder-strap.

I am aware that the use of an elastic strap is not, broadly, new; but I am not aware that it has ever before been combined with a yoke, as herein shown. It will be noticed that the sections A A B B are extended upward not simply to form shoulder-straps, but to complete the vest-like form of the corset, which I regard as essential to its comfort and neatness.

A further improvement in form and arrangement is in the bust shown in Fig. 1. The requisite swell is formed by inserting a single elliptical gore, I, between the sections A and D. The bottom of the swell is somewhat higher than in ordinary corsets, leaving a longer waist, and the whole conducing to render the figure round, trim, and symmetrical.

A common objection to corsets as ordinarily constructed arises from the fact that the steels are soon rusted and ruined by the per-

spiration from the body, there being usually but one thickness of cloth above them. To avoid this objection, I inclose the steels within double thicknesses of cloth in every case.

5 The tendency of corsets to break down over the hips at the sides is well known. I remedy this defect by combining the stiffening action of springs and cording in the manner shown in Fig. 6. The hip-sections G H are 10 corded in the manner shown in Figs. 1, 2, and 6, an extra quality of cord being used. Directly under these corded strips is attached a separate pocket, *i*, within which is inclosed the spring *n*, incased in a sheath of cloth, *o*. 15 By this means sufficient stiffness may be secured with a comparatively flexible spring, and the danger from breaking and the annoyance caused by the failure of the corset at these points are entirely avoided.

20 In the ordinary corset difficulty is had in removing the busks preparatory to washing the garment. On account of the time required and the damage caused in such removal it is quite customary to wear the corset until soiled and then throw it away. This corset is so constructed that the busks may be removed without injury to the garment and replaced with slight labor. The front pieces, C F, are folded at the edge, and the double 25 cloth is then folded over the busks *b b'* and sewed down. In the case of the section C the busk is placed far enough back from the edge or fold as to be entirely concealed thereby when right side out. A line of stitching runs 30 close to the outer edge of the busk, connecting the several parts of cloth there, and the

folded flap is then secured at the other edge of the busk by whipstitching, as shown. The busk is removed by cutting this line of stitches. In the section F, I prefer to fold the double 40 cloth close around the busk *b'* by fastening, as before. Back of this line of stitches is sewed on a separate fly, E, in which may be placed an extra steel, if desired. The plane steels in the back edges of the corsets are attached in 45 the same manner as the busk *b'*.

Having thus described my invention, what I claim as new, and desire to secure by Letters Patent, is—

1. In a corset, the section F, composed of 50 double material folded at the outer edge, with such folded edge turned back and whipstitched to the body of the section to form a pocket for the busk *b'*, substantially as described.

2. In a corset, the section C, composed of 55 double material folded at the outer edge, the double material being again turned back from the outer side and permanently stitched to the body of the section about midway of the lap, 60 the part outside thereof forming a flap or "fly," and the inner folded edge being whipstitched to the body of the section to form a pocket for the busk *b*, substantially as shown and described.

65 In testimony whereof I affix my signature in presence of two witnesses.

JOSEPHINE M. ST. CLAIRE.
